POWER PRUNING SAW

Charles H. Kenyon, Hamlin, N. Y.

Application August 22, 1952, Serial No. 305,768

1 Claim. (Cl. 30—167)

1

This invention relates to pruning saws, and more particularly to a pruning saw of the power driven type.

The main object of the invention is to provide a novel and improved power pruning saw which is simple in construction, which is easy to manipulate, and which is safe to use.

A further object of the invention is to provide an improved power driven pruning saw which is inexpensive to fabricate, which is sturdy in construction, which is light in weight, which is evenly balanced so as to be easy to manipulate, and which may be operated by one hand.

Further objects and advantages of the invention will become apparent from the following description and claim, and from the accompanying drawings, wherein:

Figure 1 is a fragmentary front elevational view of a power driven pruning saw constructed in accordance with the present invention.

Figure 2 is a side elevational view of the pruning saw of Figure 1.

Figure 3 is a rear elevational view of the cutting blade of the power saw showing a fragment of the handle guard and saw shield.

Figure 4 is a top plan view of the power driven pruning saw illustrated in Figures 1 to 3.

Referring to the drawings, the pruning saw is designated generally at 11 and comprises a tubular handle 12 having secured axially thereof to one end the electric motor 13. Rigidly secured to the opposite end of the tubular handle 12 is the enlarged cylindrical housing 14 provided with the radially extending sleeve element 15 rigidly secured thereto. Journaled transversely in the casing 14 and extending axially through the sleeve element 15 and being rotatably supported therein is the shaft 16. The shaft of motor 13, shown at 17, extends axially through the tubular sleeve 12 and is journaled in the casing 14. Secured to the end of the shaft 17 is the beveled gear 18 which meshes with a beveled gear 19 secured on the shaft 16, whereby shaft 16 is drivingly coupled to the shaft of the motor 13. Designated at 19 is a circular saw blade which is secured on the end of the transverse shaft 16.

Designated at 20 is a relatively wide, generally rectangular guard strap having the inturned end arms 21 and 22 which are respectively secured to the tubular handle 12, the outer arm 23 of the strap member 20 extending parallel to handle 12, as shown in Figure 2. Rigidly secured to the upper portion of the outer arm 23 of strap member 20 is a segment-shaped guard 24, the outer arm 23 of the strap member 20 being located

2

adjacent to and parallel to the plane of the blade 19, and the guard 24 being concentric with the shaft 16 and receiving a portion of the blade 19, as is clearly shown in Figures 1 and 3. Mounted on the top portion of the tubular handle 12 opposite the strap member 20 is a conventional switch 26 which is connected in circuit with the motor 13, the line wires 27 and 28 emerging from the switch 26 and being adapted to be connected by a suitable plug, not shown, to an electric receptacle.

The motor 13 is provided adjacent the handle 12 with the plurality of outwardly projecting lug formations 29 which are located adjacent to the base plate 30 into which the tubular handle 12 is threadedly engaged, said tubular handle being locked to said base plate 30 by a lock nut 31. The end flange 32 of the motor 13 carrying the lug formations 29 is bolted to the plate 30 by a plurality of bolts 33.

The motor shaft 17 may comprise a detachable coupling, not shown, such as a sleeve coupling, whereby the main portion of the shaft 17 may be disconnected from the motor when the pruning saw is taken apart for cleaning or repair.

In operation, the device is held by means of the tubular handle 12, the fingers of the user being protected by the rectangular guard strap 20. The switch 26 may be manipulated by the user's thumb and the blade may be placed against the stalks or twigs to be cut merely by the movement of the hand holding the device. The weight of the motor 13 substantially balances the weight of the circular saw and its associated elements on opposite sides of the portion of handle 12 which the user grips, whereby the device is easy to maneuver and may be employed over long periods of time without causing fatigue.

While a specific embodiment of an improved power pruning saw has been disclosed in the foregoing description, it will be understood that various modifications within the spirit of the invention may occur to those skilled in the art. Therefore, it is intended that no limitations be placed on the invention except as defined by the scope of the appended claim.

What is claimed is:

A power pruning saw comprising a tubular handle, an electric motor secured to one end of said handle and having its shaft extending through the handle, a transverse shaft journaled to the other end of the handle, respective meshing bevel gears on said motor shaft and said transverse shaft drivingly coupling the electric motor shaft to the transverse shaft, a circular

saw blade secured on said transverse shaft, said blade being in a plane spaced laterally outwardly from the motor, a relatively large generally rectangular guard strap secured to said tubular handle with its outer portion extending parallel to said handle and extending closely adjacent the plane of said blade, a segment-shaped guard rigidly secured to said outer portion of said strap concentrically with said blade and housing a portion of the blade adjacent said strap, and a control switch for said motor mount-
